UNITED STATES PATENT OFFICE.

MAX RICHTER, OF WYOMISSING, PENNSYLVANIA, ASSIGNOR TO TEXTILE MACHINE WORKS, OF WYOMISSING, PENNSYLVANIA, A CORPORATION OF PENNSYLVANIA.

TENSION-TAKE-UP DEVICE FOR KNITTING MACHINES.

Application filed February 3, 1928. Serial No. 251,495.

My invention relates particularly to tension take-up devices such as are employed in knitting full-fashined stockings for gripping the knitted leg fabric intermediate its length and tensioning it properly during subsequent knitting of the foot; my object being to provide an improved device for this purpose which is readily engaged and disengaged with the fabric without harm to the latter, even when formed of the sheerest chiffon, and so designed as to provide an equalized strain throughout the width of the fabric as needed for perfect production. The invention is fully described in connection with the accompanying drawing, and the novel features are clearly defined in the appended claim.

Fig. 1 is a perspective diagrammatic view indicating a knitted stocking leg having one end thereof engaged on the needles of a knitting machine and its opposite end portion hanging loosely over a usual guide rod of the machine, with my improved tension take-up device shown as intermediately engaging the fabric and connected by a strap to the usual tension take-up roll or drum.

Fig. 2 is a separate perspective view of my improved device.

In knitting full fashioned stockings it is common practice to knit the leg and heel tabs on one machine, and to then transfer such partially completed stocking to a footer machine to knit the foot portion, by outwardly spreading the heel tabs so as to form an extended straight line with the instep loops and engaging the fabric along such line on the needles of the footer. To properly tension the fabric and take it up as knitting proceeds on the footer, some means must be provided to grip the fabric and its extended heel tabs and exert a constant regulated pull thereon. Devices for this purpose have heretofore been employed in connection with a strap to the machine take-up roll or drum, but there is great need of combining in such a device simplicity and ease of applying, with avoidance of possible injury to the fabric as well as the securing of equalized strains upon it, and it is the object of my present invention to produce an improved device that will satisfactorily combine these needed features.

A usual partially knitted stocking fabric 5 is indicated in Fig. 1 of the drawings, with its heel tabs 6, 6 outwardly spread to form an

extended line with the instep loops 7, this being the position as transferred to the footer needles 8, the view indicating the finished portion of a stocking leg extending from the needles and loosely overhanging 60 rod 9 of the machine as heretofore. 10 indicates the usual take-up roll or drum which is rotated as heretofore to exert a proper tensioned take-up upon the fabric, and is commonly connected by a winding strap 11 65 to some sort of a grip device adapted to engage the fabric adjacent the line of transfer and maintain its grip thereon during the knitting of the foot.

My improved device comprises a bar or 70 plate 15, preferably shaped as shown, and of sufficient width to attach thereto the fabric 5 with its heel tabs 6, 6, and having a slotted aperture 16 to which the usual strap 11 may be connected. The heel tabs being 75 commonly formed of reenforced knitting, are not easily injured, and to engage them I employ end hooks 17, 17, which may be quickly engaged and disengaged in the fabric, one hook only at each end being 80 shown as commonly provided heretofore.

Proper engagement however of the intermediate fabric width is important so as to not only provide for desired ease and speed of applying to the fabric, but also to insure 85 against damage particularly to the at present popular sheer chiffon fabric employing light weight silk the loops of which are delicate and easily injured, both in the act of applying the device and by the equalized 90 tensioning strains imparted thereby to the fabric. With these objects in view, I employ, as shown, a row of empaling pins 18, projecting upwardly from the bar or plate 15 and arranged in a line parallel with the 95 end hooks 17, 17. These pins are adapted to pass through the fabric without harm to the latter, and to engage the same so as to evenly and sufficiently distribute the strain due to their close alinement; the passing of 100 the pins into the loop openings without danger of piercing the strands, being insured by proper dullness of the points.

The engagement of my device in operative position, indicated in Fig. 1, is readily 105 and quickly effected by first engaging the end hooks 17, 17 in the tabs 6, 6, introducing them from underneath which is facilitated by the extension of the tabs beyond the adjacent width of fabric, and permitting my 110

device to hang suspended from such hook engagement; then, after the fabric has been properly set by hand, swinging plate 15 upwardly, with hooks 17, 17 acting as hinges, which swinging movement will cause the pins 18 to impale the fabric at the proper line of loops with relation to the hook engagements so as to exert without injury an even pull on the fabric when the strap 11 is tightened to its proper tension. Such impaling of the fabric causes no damage to the yarn strands or distortion of the knitted loops due to such accurate location of the pins in the loops and the distribution of the latter across the width of the instep portion

7; and at the same time provides a simple and easily applied and removed device for the purpose desired.

What I claim is:

A tension take-up device for full fashioned hosiery knitting machines comprising a tension bar having heel tab engaging end hooks, and an intermediate row of impaling pins adapted to engage the instep portion of the fabric in a line determined by the engagement of said hooks so as to exert a practically equalized tensioning action throughout the width of the fabric. 20 25

In testimony whereof I affix my signature
MAX RICHTER.
